UNITED STATES PATENT OFFICE.

GEORGE CARL VENNUM, OF WESTFIELD, NEW JERSEY.

WATER-TUBE BOILER.

Application filed July 2, 1921. Serial No. 482,086.

My invention relates to the construction of boilers of the water tube type and has for its object to provide a boiler which will have a maximum efficiency and capacity for a given amount of surface and, at the same time, great simplicity of construction. My improved boiler is characterized in that it consists, generally speaking, of three sections. One consists of a heater section, the delivery end of which is in direct connection with the steaming section to be described, and which heater section consists of a series of rows of water tubes connected in series in such a manner that the water fed into the heater section by a pump, passes progressively from the rear to the front end of the heater section and into the steaming section, at a high rate of speed and in a single direction in the sense that there is no re-circulation of water in any part of the heater section but a steady and rapid flow from inlet end to steaming section. In order to insure a sufficiently high rate of speed in the water flowing through the heater section I find it desirable not only to connect the tube rows in series with each other but also to connect the tubes of each row in series. The heater section of my boiler is further characterized in that it is contained in a container flue of contracting area receiving the gases which have passed the steaming section at its larger end and transmitting them among the successive tube rows at a rate of flow which is maintained at high speed notwithstanding the cooling of gases and contracting of volume. By preference, the tube rows of the water heating section are of progressively decreasing length so as to fit into the contracting container but the tubes are of uniform length and uniform diameter and spacing, the contraction in the container being in the side walls only. The opening at the end of the heater section is of the unobstructed full length and width of the smaller end of the container flue.

While in designing my boiler it is not my intention that steam should be generated in the heater section, it is possible under certain conditions of operation, that some steam would be generated in the front rows of tubes and to provide for this contingency I arrange steam traps connected with the front rows of heater tubes, which traps are maintained in free communication with the steam spaces of the steaming section.

The second main section of my boiler con-

sists essentially of a tube bank directly exposed to the radiant heat of the furnace and forming the main part of a closed circuit steam generator and through which tube bank the gases are drawn in a single contracting pass from front to rear of the tube bank so that, as the gases cool and contract their speed of transmission through the tube bank is maintained at a high rate. This part of my boiler I design to operate upon water entering it at substantially boiling temperature so that the heat transmitted through the boiler tubes to the water by radiation and convection has simply the duty of converting the previously heated water into steam, and to insure that circulation in this steaming section of the boiler shall be uni-directional I provide means for protecting the return tubes of the boiler from the direct impingement of the heated gases from the furnace.

The third section of my boiler consists of a superheater located between the steamer and heater sections in the direct path of the gases as they leave the steamer section.

The prime objects which I have in view in my construction are, first, to relieve the steaming section of the duty of heating the water to the boiling point and to so construct it that it will utilize the radiant and sensible heat of the furnace gases in converting the heated water into steam with the utmost efficiency. With regard to the heater section, the prime object had in view in my construction is to maintain the temperature differences between the gases and the water in the tube rows the highest possible at all points along the line of travel and also to maintain a maximum rate of heat transfer by maintaining a high speed of gas travel through the heater section to compensate for the decreasing temperature and volume of the gases. It is also my object to insure that the gases should pass through the heater section with an even uneddying flow and for this purpose I provide for a one pass flow of gases among the water tubes and avoid baffling. Also I provide at the end of the container flue an exit opening of the full unobstructed length and width of this end of the flue. Again, I maintain the water passing through the heating section at a high speed by reason of the series connection of the tube rows and, preferably, of the tubes in the rows, and avoid all re-circulation in the heater section, both because the rapid

flow of water through the tubes facilitates heat transfer and because a rapid flow of water through the tubes tends to prevent the formation of gas or air bubbles adhering to the inside of the tubes with the well known deleterious effect of such formations. Other features of my invention will be best understood as described in connection with the drawings which illustrate a boiler construction in accordance with my invention and in which description of the figures:

Figure 1 is a longitudinal view of the boiler, with one wall partially removed and certain parts shown in section;

Fig. 2 is a plan view of the boiler, with the roof partly broken away and parts being shown in section;

Fig. 3 is a rear view of the boiler, with the flue box removed;

Fig. 4 is a section on the line 4—4, Fig. 1; showing the lower drum and the steam drum and connections between the two and also the superheater;

Fig. 5 shows a modified form in which the heater section is located below the steam generating section; and

Fig. 6 is another modified form in which the heater section is located above the steam generating section.

Referring more particularly to the drawings, the boiler is divided into a heater section A and a vaporizing section B, the same being separate and distinct except for the connections 1 and 2 through the first of which water is discharged from the heater section to the vaporization section when, and only when, it has substantially reached a vaporizing temperature, and through the second of which is discharged any steam that may be formed in the heater section.

The heater section in the embodiment shown is composed of twenty-four rows of parallel tubes 3 and 4, the tubes in row 3 being staggered relatively to the tubes 4 (Fig. 2). The ends of the tubes are held in headers 5, 6 there being a header for each of the respective ends of each row of heater tubes. As shown in the drawings, the heater tubes are divided into four sections and water is supplied through the supply pipe 7 which is connected by a valve 8 to the upper header of the rearmost row of tubes. This upper header, as shown in Fig. 3, is so constructed that water flowing into said header flows down the tube nearest to the rear valve 8 to the lower header, whence it flows upward through the remaining next tube of this row and so on through all the tubes of that row in series. It then passes to the upper header of the next succeeding row, which header is divided so that the water flows through the tubes of the second row in series to the next lower header, and so on. There is in each section of the heater an even number of tubes, so that the water

enters the top of the first tube and discharges from the upper end of the last tube in each section. The movement of the water is always from the rear of the heater section toward the front end thereof, and on account of the series arrangement, of relatively high velocity. The heater tubes are grouped in four sections and each of the three rear divisions of the heater section is connected to the supply pipe through an inlet valve 8 and an outlet valve 9. Between each two valves 8 and 9 there is another valve 10 so that the course of the water can be directed around any particular division if desired, enabling any of the three rear sections to be cut out for inspection or repair. In normal operation the valves 10 in the supply pipe 7 are closed and the valves 8 and 9 connecting the supply pipe to the several divisions of the heater are all open. In case it is desired to cut out any particular division of the heater, the valves 8 and 9 connecting that section to the supply pipe are closed and the valve 10 in the supply pipe between the two valves of the section is opened so that water flows directly past that division instead of flowing through the headers and tubes thereof. The walls of the casing of the heater are formed in sections 11, so as to be separately removable so that access can be had to any section which is cut out, thus enabling inspection and repair without entirely disconnecting the heater from the supply pipe or taking down any portion of the tubes of the heater section. The walls of the heater section have a sheet iron exterior and an asbestos lining 12. In line with the divisions between the heater sections are separating plates 13 extending from the sides of the divisions to the outer casing, which prevent the hot gases from passing through the passages between the enclosing walls and the exterior heater tubes. Adjacent to the bottom headers 5', 6' are arranged troughs 14 for receiving dust or soot which may collect in the heater section, and in these troughs are screw conveyors 15 which discharge such soot or ashes into chutes 16 leading to the ash pit of the furnace proper.

The walls of the casing surrounding the heater are inclined toward one another so that the space between the walls grows narrower as the rear end of the furnace is approached. This results in maintaining the velocity of the flow of gas through all parts of the heater section, which velocity, if the passage were of uniform diameter, would decrease as the rear end of the furnace is approached since the gases as they approach the rear end become cooler and thereby contract so as to occupy less space. By tapering the walls properly the rate of flow of the gas through the heater section can be maintained substantially constant at all

points and can be even made to increase as the rear end of the heater is approached. The rear end of the heater is connected with the flue box 17, which, in turn, is connected 5 to the stack (not shown).

The forward division of the heater section is constructed in a manner similar to the other divisions, but has but one connection with the heater supply pipe 7 so that 10 it cannot be cut out of service, and the three front rows of tubes are provided at their upper ends with vertically elongated headers 18 having adjacent to the ends of the tubes water connections which permit the flow of 15 water as above described and also having above the level of the water in said upper headers connections 19 which permit any steam which may be generated in said three front rows to pass directly to the front 20 header. This front header is connected by one or more pipes 1 to the lower part of the main steam drum 20 of the vaporizing section and by pipes 2 to the upper part thereof so that water flows from said upper 25 headers into the vaporizing section and any steam generated in the three front rows of the front division of the heater will pass directly to and mingle with the steam in the main steam drum.

30 The main steam drum 20 forms a part of the steam generating or vaporizing section, which consists of an inclined bank of tubes 21 of relatively small size located above the fuel bed in the fire box 22. The upper and 35 lower ends of these tubes are connected to drums or headers 23 and 24 respectively, one of said drums, 23, being vertical beneath the main steam drum 20 and the other, 24, being in the same horizontal plane therewith. These drums are connected to the main steam drum by large connecting pipes 30 and 26 respectively. The surface of the pipes 25 exposed to the gases is therefore 40 comparatively small relatively to the amount of water contained therein, thus reducing the tendency toward the formation of steam in those connections. Furthermore, the vertical connections 26 between the main steam drum and the lower drum are separated 45 from the furnace by the fire walls at 27 so that hot gases do not come in contact therewith at all, thus insuring against the generation of steam in those vertical connections. The result of this construction is that 50

55 the flow of water through the vaporizing section is uni-directional, being down through the vertical connections 26 and upward through the inclined tubes 21, which latter are directly exposed to the radiant heat of the fire box and to the hottest gases. The steam in the vaporizing section is, 60 therefore, produced in the inclined pipes 21 and flows upward therethrough to the header 24 connected to the upper ends 65 thereof, from whence it flows through the

large pipes 25 to the main steam drum 20. The connections 25 being large are only partially filled with water and thus permit the free circulation of both water and steam and the free release of steam from the water.

In order to increase the tube surface exposed to the direct effect of radiant heat the inclined tubes in the front row of the bank 21 of the vaporizing section are spaced 75 apart twice the distance of the tubes in the remaining rows. This exposes tubes in the second row to the radiant heat and thereby increases the surface so exposed and the amount of radiant heat absorbed.

In order to have this radiant heat act most efficiently it is necessary to keep the tubes exposed to the effects of it free from dust, slag and soot, and in order to enable that to be easily done I pass through the 80 upper and lower drums a series of tubes 28 whose axes are in line with the spaces between the tubes of the front row of the bank 21. This enables me to insert a steam nozzle from time to time through the openings and 85 discharge steam in the spaces between the tubes of the front row so as to keep those tubes relatively clear from slag, soot, etc.

The inclined tubes 21 are so arranged as 90 to comprise a bank, the width of which decreases from front to rear, each row of tubes from front to rear being shorter than the row in front. The ends of this bank are 95 embraced by two inclined walls 29 which merge with the vertical walls 27, which vertical walls form a passage directing the 100 hot gases to the heater section, which passage contains the superheater elements 30. On account of the inclined walls 29 above referred to a wide space is provided for the 105 tubes exposed to radiant heat and the passage containing the other vaporizing tubes is rapidly contracted so that the rate of flow of hot gases as they pass between the vaporizing tubes and impinge thereon is kept 110 substantially constant. The contraction of this passage is quite rapid because the vaporization absorbs heat rapidly, resulting in a rapid reduction in the volume of the 115 gas. The construction is preferably such as to so increase the velocity of flow that the convection heating effect may be maintained fairly constant upon all the inclined tubes 120 of the vaporizing section.

In providing a superheater I introduce 125 into the upper drum adjacent each end two pipes 31 whose upper ends extend above the water line, and to whose lower ends two headers 32 are connected. From each of these headers U-shaped pipes 30 extend 130 whose other ends are connected to other headers 32' which are in turn provided with discharge ports 33 through which the steam is conducted from the boiler. In this way steam which is collected in the main steam

drum before it leaves the boiler is passed through one of the two members of the superheater construction and is thereby subjected to gases whose temperature is very high, being the maximum fire box temperature less than absorbed by producing vaporization.

In the operation of the furnace as a whole water is supplied to the heater section 19 through the supply pipe 7, being forced to progress in the ordinary manner by a suitable pump (not shown), and proceeds progressively from the cool rear end of the water heater to the front hot end thereof, 15 becoming gradually warmer without any re-circulation. It is then fed through the pipes 1 into the vaporizing section, and flows downward through the pipes 26 to the lower drum 23, whence it flows upward through 23 the inclined pipes 21 to the upper front drum 24, being at that time partially converted into steam, which steam is collected in the upper front drum 24 and led to the main steam drum 20 where it mingles with 25 any steam which may have reached that drum from the forward division of the heater section.

In this way there is no re-circulation of water between the steamer section and the 30 heating section. There is no interference between those two sections, the heating section acting to progressively heat the water so as to discharge it to the vaporizing section in a condition to be converted into 35 steam. On account of the steam connection between the heater section and the main steam drum, the heater section can be safely run at such a heat as to generate steam in its forward division, a thing which is to be 40 guarded against in connection with so-called economizers in use at the present time.

Fig. 5 shows another arrangement of the heater and vaporizing sections. The vaporizing section in this case is upright as in Fig. 45 1. The passage containing the heater section, however, is a vertical passage, the gases being led downward through it after passing the vaporizing section. In this case the division of the heater which is nearest to the vaporizing section is connected by a pipe 34 50 with a supplemental drum 35. The drum 35 is connected to the main steam drum of the vaporizing section by a pipe 36 below the water level in both drums and by a pipe 37 55 above the water level in both drums. Cool water is fed into the inlet at the lower end of the heater section. The operation is substantially the same as the operation of the apparatus shown in Figs. 1 to 4.

60 Fig. 6 shows still another arrangement in which the vaporizing section is turned through an angle of 90 degrees and the heater section is located above the same, the gases passing directly upward through the 65 vaporizing section to the heater section and

thence to the flue. In this case the lowermost division of the heater is the section in which the water is the hottest and this section is formed with a steam trap 38 which is connected by a tube 39 to a supplemental drum 40. The highly heated water and any steam which may be formed in the heater section goes upward through the pipe 39 to the supplemental drum 40. Leading from this drum is a pipe 41 which extends upward 75 half way above the bottom of that drum and connects with the lower end of the main steam drum 42 so that while the drum 40 is kept half filled with water, water flows from the drum 40 to the drum 42. A pipe 43 80 which extends into the upper half of the drum 40 is connected with the upper portion of the drum 42 and serves to conduct steam which may be discharged by the lower heater section into the drum 40 directly to the 85 steam space in the drum 42.

From the foregoing it will be seen that my invention may be adapted to varying conditions which may exist in different plants, it being possible to locate the elements in a 90 horizontal series or to locate the heater below the vaporizing section or above the same or at an angle thereto. In every case the arrangement provides for a single pass of the hot gases and does not require baffle plates 95 or other devices which are liable to form gas pockets which interfere with the efficiency of operation.

As will be evident to those skilled in the art, my invention permits of various modifications without departing from the spirit thereof or the scope of the appended claims. 100

What I claim is:

1. A boiler comprising a closed circuit steaming section of the water tube type having a tube bank made up of multiple rows of tubes and directly exposed to the heat of the fire box, in combination with means for directing the fire gases through the tube bank of the steaming section in a single pass 105 and through a contracting area, so as to maintain said gases at high speed of transmission, a water heating section connected to directly supply the steaming section and made up of multiple rows of water tubes 110 connected together in series so as to maintain a one direction flow of water therein from rear to front and directly into the steaming section, said water heating section being of such heating capacity as will heat 115 the water to approximately the steaming temperature before delivering it to the steaming section and a flue container for said heating section connected to receive the gases directly from the steaming section and contracting from front to rear so as to maintain the gases at a high speed of transmission. 120

2. A boiler comprising a closed circuit steaming section of the water tube type hav- 125 130

ing a tube bank made up of multiple rows of tubes and directly exposed to the heat of the fire box, said steaming section having return tubes for the downward flow of water located outside of the path of the fire gases, in combination with means for directing the fire gases through the tube bank of the steaming section in a single pass and through a contracting area, so as to maintain said gases at high speed of transmission, a water heating section connected to directly supply the steaming section and made up of multiple rows of water tubes connected together in series so as to maintain a one direction flow of water therein from rear to front and directly into the steaming section, said water heating section being of such heating capacity as will heat the water to approximately the steaming temperature before delivering it to the steaming section and a flue container for said heating section connected to receive the gases directly from the steaming section and contracting from front to rear so as to maintain the gases at a high speed of transmission.

3. A boiler comprising a closed circuit steaming section of the water tube type having a tube bank made up of multiple rows of tubes and directly exposed to the heat of the fire box, in combination with means for directing the fire gases through the tube bank of the steaming section in a single pass and through a contracting area, so as to maintain said gases at high speed of transmission, a water heating section connected to directly supply the steaming section and made up of multiple rows of water tubes in which the tubes of each row are connected in series and each successive row is also connected in series so as to maintain a one direction rapid flow of water through said heating section and into the steaming section, said water heating section being of such heating capacity as will heat the water to approximately the steaming temperature before delivering it to the steaming section and a flue container for said heating section connected to receive the gases directly from the steaming section and contracting from front to rear so as to maintain the gases at a high speed of transmission.

4. A boiler comprising a closed circuit steaming section of the water tube type having a tube bank made up of multiple rows of tubes and directly exposed to the heat of the fire box, in combination with means for directing the fire gases through the tube bank of the steaming section in a single pass and through a contracting area, so as to maintain said gases at high speed of transmission, a water heating section connected to directly supply the steaming section and made up of multiple rows of water tubes of equal height and progressively

decreasing length from front to rear, said rows of tubes being connected together in series so as to maintain a one direction flow of water therein from rear to front and directly into the steaming section, said water heating section being of such heating capacity as will heat the water to approximately the steaming temperature before delivering it to the steaming section and a flue container for said heating section connected to receive the gases directly from the steaming section and contracting from front to rear so as to maintain the gases at a high speed of transmission.

5. A boiler comprising a closed circuit steaming section of the water tube type having a tube bank made up of multiple rows of tubes and directly exposed to the heat of the fire box, in combination with means for directing the fire gases through the tube bank of the steaming section in a single pass and through a contracting area, so as to maintain said gases at high speed of transmission, a water heating section connected to directly supply the steaming section and made up of multiple rows of water tubes connected together in series so as to maintain a one direction flow of water therein from rear to front and directly into the steaming section, said water heating section being of such heating capacity as will heat the water to approximately the steaming temperature before delivering it to the steaming section, a flue container for said heating section connected to receive the gases directly from the steaming section and contracting from front to rear so as to maintain the gases at a high speed of transmission and a superheater located in the gas pass between the steaming and heating section of the boiler.

6. A boiler comprising a closed circuit steaming section of the water tube type having a tube bank made up of multiple rows of tubes and directly exposed to the heat of the fire box, said rows of tubes connecting at top and bottom with common headers, said steaming section having also a steam and water drum connected to the common headers of the tube bank, in combination with means for directing the fire gases through the tube bank of the steaming section in a single pass and through a contracting area, so as to maintain said gases at high speed of transmission, a water heating section connected to directly supply the steaming section and made up of multiple rows of water tubes connected together in series so as to maintain a one direction flow of water therein from rear to front and directly into the steaming section, said water heating section being of such heating capacity as will heat the water to approximately the steaming temperature before delivering it to the

steaming section and a flue container for said heating section connected to receive the gases directly from the steaming section and contracting from front to rear so as to maintain the gases at a high speed of transmission.

7. A boiler comprising a closed circuit steaming section of the water tube type having a tube bank made up of multiple rows of tubes and directly exposed to the heat of the fire box, said rows of tubes connecting at top and bottom with common headers, said steaming section having also a steam and water drum connected to the common headers of the tube bank, in combination with means for directing the fire gases through the tube bank of the steaming section in a single pass and through a contracting area, so as to maintain said gases at high speed of transmission, a water heating section connected to directly supply the steaming section and made up of multiple rows of water tubes in which the tubes of each row are connected in series and each successive row is also connected in series so as to maintain a one direction rapid flow of water through said heating section and into the steaming section, said water heating section being of such heating capacity as will heat the water to approximately the steaming temperature before delivering it to the steaming section and a flue container for said heating section connected to receive the gases directly from the steaming section and contracting from

front to rear so as to maintain the gases at a high speed of transmission.

8. A boiler comprising a closed circuit steaming section of the water tube type having a tube bank made up of multiple rows of tubes and directly exposed to the heat of the fire box, said rows of tubes connecting at top and bottom with common headers, said steaming section having also a steam and water drum connected to the common headers of the tube bank, in combination with means for directing the fire gases through the tube bank of the steaming section in a single pass and through a contracting area, so as to maintain said gases at high speed of transmission, a water heating section connected to directly supply the steaming section and made up of multiple rows of water tubes of equal height and progressively decreasing length from front to rear, said rows of tubes being connected together in series so as to maintain a one direction flow of water therein from rear to front and directly into the steaming section, said water heating section being of such heating capacity as will heat the water to approximately the steaming temperature before delivering it to the steaming section and a flue container for said heating section connected to receive the gases directly from the steaming section and contracting from front to rear so as to maintain the gases at a high speed of transmission.

GEORGE CARL VENNUM.
